UNITED STATES PATENT OFFICE

WILLIAM H. BRESNAHAN, OF LYNN, MASSACHUSETTS, ASSIGNOR, BY MESNE ASSIGNMENTS, TO COMPO SHOE MACHINERY CORPORATION, OF NEW YORK, N. Y., A CORPORATION OF DELAWARE

METHOD OF MAKING FOOTWEAR

Original application filed April 24, 1928, Serial No. 272,449. Divided and this application filed December 5, 1928. Serial No. 323,917.

This invention pertains to footwear and more particularly the boots and shoes and to a method of making the same. In a co-pending application, Serial No. 272,449, filed 5 April 24, 1928, of which this is a division, I have disclosed and claimed broadly a method of and apparatus for use in making footwear of that type in which the outer sole is permanently secured in place by means of 10 an adhesive instead of the usual fasteners, such as stitches, nails, and etc. The present invention relates to a specific application of said broad method to the production of shoes of arch supporting type, and to arch supporting shoes made in accordance therewith, and has as a general object the production of 15 a novel and improved type of arch supporting shoe in a convenient, efficient and economical manner.

20 A more specific object of the invention is to provide a process of making an arch supporting shoe in a manner such that pre-formation of the inner sole is unnecessary and that the finished shoe will include a per- 25 manently positioned hump or elevation which does not break the smooth continuity of the inner sole and which provides a proper arch support for the foot.

Many attempts have been made to pro- 30 vide shoes of usual type with arch supporting elements, but most prior attempts have necessitated special preparation of the inner and outer soles, or the employment of troublesome process steps, all of which add 35 materially to the cost of manufacture, so that arch supporting shoes can not compete in the market with ordinary shoes.

In accordance with the present invention it is possible to make arch supporting shoes 40 embodying arch supporting means of ap- proved character without affecting the external appearance of the shoe, and at a cost not substantially in excess of that of shoes of 45 ordinary type made by the same general process. In carrying my novel process into effect I prepare the inner and outer soles of the shoe in the usual way, but employ a last having a cavity in its bottom at a point corresponding to the desired position 50 of the arch support. In applying the outer

sole to the shoe bottom, I introduce an arch supporting pad of any suitable material and of proper configuration between the inner and outer soles, registering the pad with the hollow in the last, it being understood that 55 the opposite surfaces of the inner and outer soles have previously been made adhesive by the interposition of some suitable medium. The shoe, with its outer sole, is now clamped in a pressure applying mold having 60 an inflatable pad, on which the outer sole rests. Pressure fluid is admitted to the pad to inflate the latter, thus causing the sole and shoe bottom as a whole to conform closely to the bottom of the last. The interposed 65 pad forces the inner sole into the cavity in the last, thus producing a hump or elevation in the upper surface of the shoe bottom. The shoe is permitted to remain in the mould until the adhesive has set, and when re- 70 moved the parts of the shoe bottom are so firmly united as to prevent subsequent relative movement, and thus the hump is permanently retained. This hump or elevation constitutes a very effective arch support but 75 does not detract from the appearance of the shoe, requires no special shaping of the outer sole or other parts constituting the shoe bottom, and in accordance with this method may be provided without substantially in- 80 creasing the cost of production.

In the accompanying drawing I have il- 85 lustrated a shoe made in accordance with the present invention, together with certain instrumentalities employed in the process of making this shoe, it being understood that the invention is not in any way restricted to shoes of the particular style or configura- 90 tion illustrated, and that the arch supporting means may be disposed at other positions than that shown, in accordance with the demands of each particular case.

In the drawing:

Fig. 1 is a diagrammatic side elevation of a shoe mounted upon a last and with parts of the upper, sole and last broken away and in section to show the arch supporting hump;

Fig. 2 is a composite view showing an arch supporting pad of one desirable type, in plan and in section, respectively;

Fig. 3 is a composite view showing a shoe last in bottom plan view, and in side elevation (partly in section), respectively, indicating the provision of a hollow or cavity; 5 and

Fig. 4 is a vertical section illustrating a molding press useful in carrying the present process into effect.

Referring to the drawing, the numeral 10 designates the upper of a shoe having an outer sole 2 and an inner sole 3. In preparing the shoe according to the present process, one may make the inner and outer soles of normal construction, that is to say, of a 15 construction such as is usually employed in shoes of the particular style and grade to be manufactured and without reference to the arch supporting feature. One then selects a last 4 of the proper shape for use in 20 making a shoe of the selected style, but modifies this last by forming a cavity 6 in its lower surface. This cavity is formed at the desired location of the arch supporting elevation or hump and may be made of any suitable contour in accordance with the desired 25 shape of the hump or elevation. I also provide an arch supporting pad 5 of rubber, leather, fiber, or the like having a contour generally similar to that of the cavity 6.

30 The upper 1 and inner sole 3 are assembled and the upper is lasted upon the last 4 in usual manner, employing any desired form of connection for uniting its margin to the inner sole. The pad 5 is now placed 35 in contact with the outer surface of the inner sole and in registry with the cavity 6 in the last bottom, and the outer sole is disposed in contact with the shoe bottom. Before registering the outer sole with the shoe bottom, 40 one or both of the contacting surfaces is coated with a suitable adhesive. The outer sole is now subjected to pressure, preferably in a mold in which the parts may be clamped and held in assembled relation while the adhesive is setting.

A suitable mold for the purpose is illustrated in Fig. 4. This mold comprises a frame 7 adapted to support a pressure-applying pad 8. Preferably this pad is hollow and adapted to be inflated by means of a pressure fluid, which may be admitted through a valved inlet 9 and exhausted through a valved outlet 10. The frame also comprises an upright 11 to which is pivotally secured a clamping bar 12. 50 This bar preferably carries a spindle 13 adapted to enter the usual socket in the last, and a forepart pad 14 adapted to engage the forepart of the upper. A retaining element 15 is adapted to engage one of a series of notches in the end of the bar 12 to hold the latter in adjusted position.

After the outer sole has been registered with the shoe bottom as above described, (the pad having been interposed between the soles) it is set upon the upper surface of the

pad 8 and the bar 12 is swung downwardly to engage the pin 13 with the socket in the last, at the same time bringing the pad 14 into contact with the forepart of the upper. The retaining member 15 is now engaged with the bar 12, and pressure fluid is admitted through the inlet 9 to inflate the pad 8. This pressure fluid may be compressed air or liquid, as may be preferred, and the pressure is sufficient to force the pad 5 upwardly until the inner sole bulges up into the cavity 6 of the last. Since the outer sole is usually heavier than the inner sole, the interposed pad 5 makes itself apparent only in a bulging of the inner sole, the outer surface of the outer sole retaining its normal configuration. The parts are allowed to remain in the mold until the adhesive between the inner and outer soles is set, thus permanently uniting the inner and outer soles and at the same time retaining the bulge 6 formed in the inner sole above the pad. When the shoe is released from the mold, after the adhesive has set, its external appearance is not substantially different from that of an ordinary shoe of the same general construction and same style, but the inner sole presents a hump constituting an arch support at the desired point. This hump does not break the smooth continuity of the inner sole, although providing a proper support for the metatarsal arch of the foot. The support thus furnished is very efficient for the purpose, but as above described does not necessitate any change in the preparation of the inner and outer soles, and adds but little to the cost of production of the shoe.

Since certain changes in carrying out the above method, and certain modifications in the article which embody the invention may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. That method of providing a shoe, having inner and outer soles, with an arch support, which comprises as steps providing an arch-supporting pad, providing a last having a cavity in its under surface, lasting the shoe upon the last, disposing the pad between the inner and outer soles and in registry with said cavity, the opposed surfaces of the inner and outer soles being adhesive, and subjecting the shoe to pressure whereby permanently to unite the outer and inner soles and to cause

the inner sole to protrude into the cavity of the last.

2. That method of making an arch-supporting shoe which comprises as steps assembling an upper and inner sole and lasting the upper upon a last having a cavity in its bottom, preparing an outer sole, disposing a pad in contact with the inner sole in registry with the cavity in the last bottom, applying the outer sole, with interposed adhesive, to the bottom of the shoe, and subjecting the outer sole to pressure during the setting of the adhesive, the pressure being sufficient to cause the interposed pad to force the inner sole into the cavity in the last, thereby providing a hump on the upper surface of the inner sole.

3. That method of making arch-supporting shoes which comprises as steps lasting an upper and an inner sole of normal type on a last having a cavity in its bottom, preparing an outer sole of normal type, preparing a pad, disposing the pad in contact with the outer surface of the inner sole in registry with the cavity in the last, applying the outer sole to the shoe bottom, first interposing adhesive between the outer sole and shoe bottom, and subjecting the outer sole to fluid pressure whereby to cause the pad to force the inner sole into the cavity in the last bottom and retaining the parts in such position until the adhesive has set.

4. That method of making an arch supporting shoe which includes as steps, in combination, placing a lasted upper upon a last having a cavity in its bottom, disposing a pad in contact with the inner sole in registry with the cavity in the last bottom and applying pressure to the pad sufficient to cause the pad to force the inner sole into the cavity in the last, thereby providing a hump on the upper surface of the inner sole.

5. That method of making an arch supporting shoe which includes as steps, in combination, assembling an upper and an inner sole and lasting the upper upon a last having a cavity in its bottom, preparing an outer sole, disposing a pad in contact with the inner sole in registry with the cavity in the last bottom, positioning the outer sole over the inner sole and the pad, applying pressure to the bottom of the outer sole sufficient to cause the interposed pad to force the inner sole into the cavity in the last, thereby providing a hump on the upper surface of the inner sole, and securing the outer sole to the upper while the pad is in said position.

6. That method of making an arch supporting shoe which includes as steps, in combination, placing an inner sole on a last having a cavity in its bottom, disposing a pad in contact with the inner sole in registry with the cavity in the last bottom and applying pressure to the pad sufficient to cause the pad to force the inner sole into the cavity in the

last, thereby providing a hump on the upper surface of the inner sole.

Signed by me at Boston, Massachusetts this 4th day of December 1928.

WILLIAM H. BRESNAHAN.
